UNITED STATES PATENT OFFICE.

ARLEY M. JOHNSON, OF BELLE CENTER, OHIO.

ROBE-LOCK FOR VEHICLES.

SPECIFICATION forming part of Letters Patent No. 698,287, dated April 22, 1902.

Application filed December 28, 1901. Serial No. 87,610. (No model.)

To all whom it may concern:

Be it known that I, ARLEY M. JOHNSON, a citizen of the United States, residing at Belle Center, in the county of Logan and State of Ohio, have invented a new and useful Robe-Lock for Vehicles, of which the following is a specification.

This invention relates to a device for locking robes to some stationary portion of a vehicle.

The object of the invention is to provide a simple and effective device for securing a robe to a vehicle for preventing its loss either by dropping from the vehicle or by its being stolen therefrom.

Figure 1 of the accompanying drawings represents a perspective view of a portion of a vehicle, showing a lap-robe disposed therein and having this improved lock applied. Fig. 2 represents a longitudinal vertical section of this robe-lock applied and in locked position. Fig. 3 represents a perspective view of the two members of the robe-lock detached.

The same reference-numerals indicate corresponding parts in all the figures.

In the form illustrated in the drawings a plate 10 is shown adapted for attachment to a lap-robe and a clamp 20 for engaging a portion of a vehicle and provided with means for fastening it to the plate 10. The plate 10 is preferably made in the form of a metal strip rounded at its opposite ends and provided with longitudinally-extending lines of perforations, as 11, through which the plate is attached to the robe 50, preferably by means of a wire thread, which would more securely attach the plate to the robe than if the ordinary sewing-thread were used. The end 12 of the plate 10 projects beyond the edge of the robe 50 and is provided with an aperture 13 therein for a purpose hereinafter described. The clamp 20 is preferably formed of a plate bent or folded at the middle thereof to form a large loop 21, adapted to encircle a rod. The outer ends 22 and 23 of the clamp 20 are provided near their extremities with registering apertures 24 and 25. The end 12 of the plate 10 is designed to be inserted between the ends 22 and 23 of the clamp 20 and the apertures 13 therein disposed so as to register with the apertures 24 and 25 of the clamp 20. A padlock 30 is preferably used to secure these

members together by passing its hasp through the registering apertures 13, 24, and 25.

In the use of the device the plate 10 is fastened to the robe 50, as described, by means of a wire thread and has its end 12 extending beyond the edge of the robe. The clasp or clamp 20 is then passed around any suitable rod of a vehicle—such as the dashboard-rod or, as shown, the seat-rod—and the two ends 22 and 23 are so disposed as to clasp the end 12 of the plate 10 between them, with the apertures 13, 24, and 25 registering. The padlock 30 is then passed through the apertures and locked, whereby the robe is securely fastened to the vehicle.

I claim as my invention—

1. In combination with a lap-robe, a plate attached thereto, and having a projecting end provided with an opening, a clamping member secured to an anchoring device and having arms to receive the projecting end of the plate between them, said arms having openings to register with that in the plate, and a locking device to engage said registering openings and secure said plate to said clamp, substantially as described.

2. The combination with a lap-robe of a plate having perforations therein and an aperture at one end thereof, means for attaching said plate to said robe, and a clamp having a loop for engaging a rod, and apertured arms connected with said loop and adapted to engage said plate on opposite sides thereof, and means for locking said plate and arms together.

3. A robe-locking device comprising a plate having longitudinally-aligned perforations disposed along the opposite sides thereof and provided with an aperture at one end thereof, and a clamping member in the form of a plate folded upon itself at its center thereby forming a loop for engaging a rod, the end of said plate extending in the same direction in parallel planes and provided with means for attaching them to said perforated plate.

In testimony that I claim the foregoing as my own I have hereto affixed my signature in the presence of two witnesses.

ARLEY M. JOHNSON.
